UNITED STATES PATENT OFFICE

2,563,840

SPHERICAL TRIANGLE CALCULATOR

Robert J. Hundhausen, Brentwood, Mo.

Application September 2, 1947, Serial No. 771,746

3 Claims. (Cl. 33—1)

(Granted under the act of March 3, 1883, as amended April 30, 1928; 370 O. G. 757)

1

The invention described herein may be manufactured and used by or for the Government of the United States for governmental purposes without the payment to me of any royalty thereon in accordance with the provisions of the act of April 30, 1928 (Ch. 460, 45 Stat. L. 467).

My invention relates to spherical triangle calculators and particularly to one which accurately visualizes problems and enables an operator to accurately visualize his problem and, without resorting to mathematical calculations, to solve numerous spherical angle problems, including both right angle and oblique spherical triangles, as well as to solve numerous astronomical, geological, and mining problems.

In the accompanying drawings:

Figure 1 is a perspective view of my device.

Figure 2 is a plan view.

Figure 3 is an enlarged section, looking outwardly from the center of the frame.

Figure 4 is an enlarged detail on the line 4—4 of Figure 3.

In these drawings:

A base 11 rigidly supports four columns 12, which in turn rigidly hold a separable frame 13 (Figures 1 and 2). The frame 13 is divided on the diametrical plane 13a, the two halves being coupled by four screws 39 and two coupling plates 13b.

The frame 13 (Figures 3 and 4) is provided with an upper circular groove 14 of T-shape section and a similar lower circular groove 15 also of T-shape. The frame 13 is graduated adjacent to a central aperture and is also provided with an upper internal groove 16 for a graduated ring 17. The frame 13 is provided with a second internal groove 18 for a second graduated ring 19. These rings 17 and 19 correspond to those for the upper and lower motions of a surveyor's transit.

Upon the ring 17 (Figure 4) there are rigidly secured two supporting bearing blocks 20, each having a lateral semi-circular groove 21 for companion arcuate lugs 22 of blocks 23 which are rigidly secured to a semi-circular plate 24 at opposite ends of a diameter with the centers of curvature of said lugs 22 in exact alignment with said diameter.

An arcuate scale member 25 graduated for ninety degrees is rigidly supported by and in a plane perpendicular to the ring 17 and is frictionally engaged by the edges of a marginal slot 26 in the plate 24, the said slot 26 being ninety degrees from the axis of rotation of said plate 24.

The groove 14 in the frame 13 guides a downwardly extending projection 27 of a slide 28 to which is rigidly attached a graduated quadrant

29 which is terminally pivoted to said smaller arcuate scale member 25 by a pin 30.

The above described elements of my device which are mounted above a plane midway of the frame 13 are duplicated below said horizontal plane; the ring 19 supporting companion bearing blocks 31 (Figure 4) which are engaged by companion lugs 32 of blocks 33 to which blocks 33 is rigidly attached a second semi-circular plate 34 having a marginal slot 35. The arcuate extent of the blocks 23 and 33 is ninety degrees minus the thickness of the plates 24 and 34, respectively. A second arcuate scale member 36 is also graduated for ninety degrees and is frictionally engaged by the sides of said slot 35 and is rigidly attached to the ring 19. A second graduated quadrant 37 is mounted on a slide corresponding to slide 28 which slide is supported in the downwardly open circular slot 15 and is pivoted to the scale member 36 by a pin 38. Referring to Figures 1 and 2, it is apparent that by moving the quadrants 29 and 37 to the same side of the separable ring 13, the opposite side of the ring 13 may be removed by unscrewing two screws 39 and one screw 39a, thereby making possible the disassembly of my device whenever necessary.

My device provides a means for mechanically solving problems involving three dimensions and may be easily adjusted for an infinite combination of variables. The answers to problems may be read directly on my device, for example, to obtain data for plotting geologic maps, for use in the fields of mathematics, astronomy, surveying, mining and the like.

35 Among other problems which may be solved with my device are:

1. In mining; determining the pitch and bearing of the line of intersection of two planes (veins, faults, etc.)

40 2. The apparent dip of a plane cut by a geological section.

3. The strike and dip of a plane; given the bearings and dip angles of two non-parallel lines.

45 4. The solution of any right spherical triangle; knowing any two parts in addition to the right angle.

5. The dihedral angle between any two planes.

6. The solution of oblique spherical triangles knowing three of the principal parts.

50 The solution of a solar problem is simply a particular problem in the solution of a spherical triangle after the usual corrections are made on account of latitude and altitude.

There are suitable graduations on the margins 55 of each of the movable parts as well as on that of

the frame 13 which serve for setting any known angle and for reading the answers to the problems to be solved. It will be observed that a center point, common to both plates 24 and 34, always lies on the line of intersection of the planes of these plates and that the ninety degree quadrants 29 and 37 may be revolved about a vertical axis passing through the centers of both plates 24 and 34 thereby generating an imaginary hemisphere. This center point is also in the axis of rotation of the two rings 17 and 19 and is midway between the planes of the two rings and corresponds to the center of a sphere. All movable elements of this device revolve about axes which pass through this center point and a horizontal plane midway between said two graduated rings will contain the diametrical axes of the plates 24 and 34. This horizontal plane therefore contains an equatorial circle dividing the imaginary sphere into two hemispheres. These imaginary hemispheres are generated when said plates 24 or 34 are rotated about their axes.

One of the features of my invention is the provision of means for visualizing any desired position of inclination ("dip") and direction ("strike") irrespective of the attitude of either to the other.

Both the diametrical axes and vertical axis of my two plates are imaginary, but real in the sense that they are true axes of revolution. Each plate revolves about a vertical axis because it is supported horizontally on its edges in parallel circular slots in the frame 13 and may be revolved about its diametrical axis because it is supported in my bearing blocks 20 or 31 which have their centers aligned with said axis.

While I have shown and described a preferred embodiment of my invention, changes may be made in the construction and arrangement without departing from the spirit and scope of the invention as disclosed herein.

What I claim is:

1. A device for visualizing and mechanically solving problems in spherical trigonometry and analogous problems comprising a suitable supporting base, a frame provided with a central circular aperture, upper and lower grooves concentric with said aperture and two internal grooves equidistant from and parallel with a central section of said frame, said frame being separable along a diameter of said circular aperture, means for detachably coupling said frame sections, means for supporting said frame above said base, a ring having a supporting portion extending into the upper of said internal grooves and freely movable therein, a pair of arcuate bearings mounted on said ring at diametrically opposite points, a semi-circular plate provided with a marginal slot secured to said arcuate bearings with an axis of rotation midway between and parallel with the planes of said internal grooves, a slide provided with an interlocking extension mounted to move in the upper concentric groove, a graduated quadrant rigidly supported by said slide in a plane perpendicular to the plane of said frame, a graduated arcuate scale member rigidly supported by and perpendicular to said ring and passing through said marginal slot in said semi-circular plate, a pin pivotally connecting said graduated quadrant and said arcuate scale member, a second ring extending into the lower of said internal grooves and freely rotatable therein, a second pair of arcuate bearings mounted on said second ring at diametrically opposite points, a second semi-circular plate provided with a circumferential slot

fastened to said arcuate bearings with an axis of rotation midway between and parallel with the planes of said internal grooves, a second slide provided with an interlocking extension mounted in the lower of said concentric grooves, a second graduated quadrant rigidly supported by said second slide in a plane perpendicular to the plane of said frame, a second graduated arcuate scale member rigidly supported by and perpendicular to said second ring and passing through said marginal slot in said semi-circular plate, and a second pin pivotally connecting said graduated quadrant and said second arcuate scale member whereby said device is adapted for solving problems involving spherical triangles having points and lines of intersection lying on any part of a spherical surface.

2. A device for visualizing and mechanically solving problems in spherical trigonometry and analogous problems comprising a suitable supporting base, a frame provided with a central circular aperture, a groove in one face of said frame adapted to interlock with a sliding member and concentric with said central aperture and an internal groove parallel with a plane face of said frame, said frame being separable along a diameter of said circular aperture, means for detachably coupling said frame sections, means for supporting said frame above said base, a graduated ring having a supporting portion extending into said internal groove and freely movable therein, a pair of arcuate bearings mounted on said graduated ring at diametrically opposite points, a semi-circular plate provided with a marginal slot secured to said arcuate bearings, a slide provided with an interlocking extension mounted to move in said concentric groove, a graduated quadrant rigidly supported by said slide in a plane perpendicular to the plane of said frame, a graduated arcuate scale member rigidly supported by and perpendicular to said graduated ring and passing through said marginal slot in said semi-circular plate, and a pin pivotally connecting said graduated quadrant and said arcuate scale member.

3. A device for visualizing and mechanically solving problems in astronomy as well as analogous problems, which includes a suitable supporting base, a plurality of supporting columns fastened to said base, an annular frame formed of separable sections fastened to said columns, provided with two parallel internal grooves, also provided with an upper circular groove of T-shape section and a similar lower groove, means for detachably coupling said frame sections, an upper calculating portion comprising a ring having a supporting portion extending into the upper of said internal grooves and freely movable therein, a pair of arcuate bearings mounted on said ring at diametrically opposite points, a semi-circular plate provided with a marginal slot secured to said arcuate bearings with an axis of rotation midway between and parallel with the planes of said internal grooves, a slide provided with an interlocking extension mounted to move in the upper circular groove, a graduated quadrant rigidly supported by said slide in a plane perpendicular to the plane of the annular frame, a graduated arcuate scale member rigidly supported by and perpendicular to said ring and passing through said marginal slot in said semi-circular plate, a pin pivotally connecting said graduated quadrant and said arcuate scale member, and a lower calculating portion comprising a second ring extending into the lower of said internal grooves in said annular frame and freely rotata-

ble therein, a second pair of arcuate bearings mounted on said second ring at diametrically opposite points, a second semi-circular plate provided with a circumferential slot and fastened to said arcuate bearings with an axis of rotation midway between and parallel with the planes of said internal grooves, a second slide provided with an interlocking extension mounted in the lower of said circular grooves, a second graduated quadrant rigidly supported by said second slide in a plane perpendicular to the plane of said annular frame, a second graduated arcuate scale member rigidly supported by and perpendicular to said ring and passing through said marginal slot in said semi-circular plate, and a second pin pivotally connecting said graduated quadrant and said second arcuate scale member whereby said upper and lower calculating portions which are

mounted on a common annular frame provide a means for solving problems involving spherical triangles having points and lines of intersection lying on any part of a spherical surface.
